UNITED STATES PATENT OFFICE.

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS.

DESIGN FOR A STANDARD FOR MOTION-PICTURE-PROJECTING MACHINES OR THE LIKE.

Application filed December 14, 1928. Serial No. 29,272. Term of patent 14 years.

To all whom it may concern:

Be it known that I, ALBERT S. HOWELL, a citizen of the United States, residing at Chicago, in the county of Cook and State of Illinois, have invented a new, original, and ornamental Design for Standard for Motion-Picture-Projecting Machines or the like, of which the following is a specification, reference being had to the accompanying drawing, forming a part hereof.

In the said drawing—

Figure 1 is a side elevation of a standard

for motion picture projecting machines or the like embodying my new design.

Figure 2 is a top plan view of the same.

I claim:

The ornamental design for a standard for motion picture projecting machines or the like as shown.

In witness hereof I hereunto affix my signature this 11th day of December, 1928.

ALBERT S. HOWELL.
